UNITED STATES PATENT OFFICE.

JOHN J. LEE, OF CHICAGO, ILLINOIS.

BUTTON.

1,410,827.

Specification of Letters Patent. Patented Mar. 21, 1922.

Application filed October 30, 1920. Serial No. 420,713.

To all whom it may concern:

Be it known that I, JOHN J. LEE, a citizen of the United States, residing at Chicago, in the county of Cook and State of Illinois, have invented certain new and useful Improvements in Buttons, of which the following is a specification.

This invention relates to detachable buttons or garment fastenings and has for its primary object to provide a detachable button or the like of simple and improved construction, which can be readily attached to or detached from a garment or fabric, and which will not become accidentally detached. A further object is to provide detachable fastening means for a button of this type, which may be made small, relative to the size of the button, and also which may be employed on small buttons without rendering the same bulky or inartistic.

The invention consists in the novel constructions, arrangements and devices to be hereinafter described and claimed, for carrying out the above stated objects, and such other objects as will appear from the following description.

The invention is illustrated in certain preferred embodiments in the accompanying drawings, in which:

Figure 1 is a perspective of a button with the fastening device in open position.

Figure 2 is a plan view of the back of the button with the fastening device in closed position.

Figures 3 and 4 are sectional elevations taken on the lines 3—3 and 4—4 of Figures 1 and 2, respectively, and showing, respectively, the fastening device in opened and in closed position.

Figure 5 is a perspective, considerably enlarged, of the fastening device.

Figure 6 is a perspective view of the back of a button illustrating another form of a fastening device.

Figure 7 is a slightly modified form of device, as shown in Figure 6, and

Figure 8 is a sectional elevation taken on the line 8—8 of Figure 6 and showing in dotted lines the fastening device in open position.

For the purpose of illustrating the invention I have illustrated the button 10 as comprising a facing 11 and back 12, the facing being bent over along its edge, as shown at 13, to enclose the edge of the back 12. It is obvious that the facing 11 may be of any suitable size or material and be provided

with any suitable design, the particular construction of the button in this respect forming no part of this invention. The back 12 is preferably of thin sheet metal which possesses a certain amount of resiliency, although other materials may be used. Sheet metal is preferable because it may be made thin and reduces the bulk of the button.

The fastening device or hook 14 comprises a U-shaped loop or hook 15, one end of which is preferably pointed, as shown at 16. The other end 17 is provided with a lateral extension or arm 18, substantially at right angles thereto. The end of the extension 18 is provided with an offset portion 19 which in the construction shown is in the form of a right-angled bend. When applied to a button the extension 18 is positioned between the back plate 12 and the body of the button, the portion 17 of the loop passing through an opening 20 in the plate 12, which is of sufficient size to permit the rocking of the fastening device, as hereinafter pointed out. The offset portion 19 prevents the rocking of the fastening device when in the position shown in Fig. 2, by reason of the part 19 being then in contact with the plates 11 and 12, and maintains the hook 15 in upright or closed position. The plate 12 is also provided with a recess or opening 21 into which the portion 19 may project when the fastening device is rotated or swung a quarter turn in counterclockwise direction in Fig. 2 to the position shown in Figs. 1 and 3. In this normal opening position of the hook member the portion 19 is not engaged by the plate 12 and the fastening device may be rocked about the extension 18, so as to raise the point 16 above or out of contact with the plate 12, sufficiently to permit the button to be affixed to a garment or fabric.

If desired, the point 16 of the fastening device may be brought into the recess 21 when the same is in closed position, so as to more adequately close the loop formed by the fastening device and prevent the button from becoming unfastened, as well as concealing the point 16. Because of the resilient character of the plate 12, the portion 19 may be slightly wedged between the plate and the button 11, so as to firmly lock the hook 15 in closed position. It should be noted that the recess 21 need not be an opening through the plate 12, it being sufficient merely to provide sufficient space for the portion 19 so that the same may rotate therein to permit the opening of the fastening device.

110

For the purpose of conveniently illustrating the construction of the fastening device, I have shown the same considerably larger, relative to the size of the button, than it is necessary to make the same in practice. In this form of button it is not necessary, as in some forms, to make the hook 15 of sufficient width so when rotated, the point 16 will extend over the edge of the button. In other words, the fastening device 14 may be made as small as it is possible to conveniently make the same. The extension 18 and portion 19 may be made small so as to permit the formation of a relatively thin button.

In Figures 6, 7, and 8 I have illustrated other forms of buttons. The body of the button is preferably constructed as in the forms previously described and comprises a front portion 22 and a back portion or plate 23. In the form shown in Fig. 6 the back portion is provided with a pair of stationary hooks 24 spaced a short distance apart, and secured in position in any suitable manner to the plate 23. Opposite these hooks and positioned so as to lie between them is a movable hook 25 provided with extensions 26 extending therefrom, substantially at right angles, and preferably of non-circular cross section. The extensions 26 are positioned between the plate 23 and the front portion 22 and are arranged to hold the hook 25 in vertical position by reason of the resilient pressure of the plate 23. The hooks 24 and 25 are pointed, as shown at 27, and terminate a considerable distance above the back of the button. When the same are in closed position, as shown in Fig. 6, they form together a closed loop. The movable hook 25 may be rocked about its extension 26 so as to open this loop, as shown in dotted lines in Fig. 8. The stationary hooks 24 serve not only to form a closed loop, but to prevent a solid pull upon the hook 25, from opening this hook and permitting an accidental detachment of the button.

In Fig. 7 I have illustrated a slight modification of the structure shown in Figure 6. In this modification only one stationary hook 28 is employed. The movable hook 29 is constructed like that in the form shown in Fig. 6. For the purpose of convenient illustration of these constructions I have shown the spacing between the stationary and movable hooks as slightly exaggerated. In practice the pointed extremity of the movable hook will lie, when in closed position, as close as may be to the stationary hook.

I claim:

1. A detachable button comprising in combination a back plate, a hook member extending through an opening in said back plate, said hook member having a lateral extension adapted to be swung about said opening along the inner face of said back

plate, about which lateral extension the hook is adapted to rock when swung into normal opening position for permitting access to the point of the hook for attachment and detachment of the button, a face plate serving to hold said lateral extension pressed against the back plate, and means carried by said lateral extension independently of the hook proper adapted by cooperation with the back plate and the face plate when the hook is swung out of normal opening position to hold the hook from rocking whereby accidental detachment of the button is prevented.

2. A detachable button comprising in combination a back plate, a hook member extending through an opening in said back plate, said hook member having a lateral extension adapted to be swung about said opening along the inner face of said back plate, about which lateral extension the hook is adapted to rock when swung into normal opening position for permitting access to the point of the hook for attachment and detachment of the button, a face plate serving to hold said lateral extension pressed against the back plate, and offset means carried by said lateral extension in spaced relation to the hook proper adapted by engagement with the back plate and the face plate when the hook is swung out of normal opening position to hold the hook from rocking, whereby accidental detachment of the button is prevented, one of said plates being provided with a recess at one point about the opening for the hook member for receiving said offset in the normal opening position of the hook member for permitting the rocking of the hook member.

3. A detachable button comprising in combination a back plate, a U-shaped hook member, one arm of which extends through an opening in said back plate, said arm having a lateral extension adapted to be swung about said opening along the inner face of said back plate, about which lateral extension the hook is adapted to rock when swung into normal opening position for permitting access to the point of the hook for attachment and detachment of the button, a face plate serving to hold said lateral extension pressed against the back plate, and an offset at the end of the lateral extension in spaced relation to the hook proper adapted by engagement with the back plate and the face plate when the hook is swung out of normal opening position to hold the hook from rocking, whereby accidental detachment of the button is prevented, the back plate being provided with an opening adapted to receive said offset when the hook member is in normal opening position for permitting the rocking movement of the hook member.

JOHN J. LEE.
